(57) **CLAIM**

The ornamental design for a lens component, as shown and described.

DESCRIPTION

FIG. 1 is a front, top, and left side perspective view of a lens component;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;
FIG. 7 is a bottom plan view thereof;
FIG. 8 is a rear, bottom, and right side perspective view thereof;
FIG. 9 is a front, bottom, and right side perspective view thereof;
FIG. 10 is a front, bottom, and left side perspective view thereof;
FIG. 11 is a front, top, and left side perspective view of another embodiment of a lens component;
FIG. 12 is a front elevational view thereof;
FIG. 13 is a rear elevational view thereof;
FIG. 14 is a left side elevational view thereof;
FIG. 15 is a right side elevational view thereof;
FIG. 16 is a top plan view thereof;
FIG. 17 is a bottom plan view thereof;
FIG. 18 is a rear, bottom, and right side perspective view thereof;
FIG. 19 is a front, bottom, and right side perspective view thereof;
FIG. 20 is a front, bottom, and left side perspective view thereof;
FIG. 21 is a front, top, and left side perspective view of another embodiment of a lens component;
FIG. 22 is a front elevational view thereof;
FIG. 23 is a rear elevational view thereof;
FIG. 24 is a left side elevational view thereof;

FIG. 25 is a right side elevational view thereof;
FIG. 26 is a top plan view thereof;
FIG. 27 is a bottom plan view thereof;
FIG. 28 is a rear, bottom, and right side perspective view thereof;
FIG. 29 is a front, bottom, and right side perspective view thereof;
FIG. 30 is a front, bottom, and left side perspective view thereof;
FIG. 31 is a front, top, and left side perspective view of another embodiment of a lens component;
FIG. 32 is a front elevational view thereof;
FIG. 33 is a rear elevational view thereof;
FIG. 34 is a left side elevational view thereof;
FIG. 35 is a right side elevational view thereof;
FIG. 36 is a top plan view thereof;
FIG. 37 is a bottom plan view thereof;
FIG. 38 is a rear, bottom, and right side perspective view thereof;
FIG. 39 is a front, bottom, and right side perspective view thereof; and,
FIG. 40 is a front, bottom, and left side perspective view thereof.
The features illustrated in phantom line form no part of the claimed design.
